UNITED STATES PATENT OFFICE

WALFRED F. WESTERLIND, OF ROCKFORD, ILLINOIS

DESIGN FOR A VACUUM PRESSURE BOTTLE OR SIMILAR ARTICLE

Application filed January 26, 1933. Serial No. 47,001. Term of patent 3½ years.

To all whom it may concern:

Be it known that I, WALFRED F. WESTERLIND, a citizen of the United States, and a resident of the city of Rockford, county of Winnebago, and State of Illinois, have invented a new, original, and ornamental Design for a Vacuum Pressure Bottle or Similar Article, of which the following is a specification, reference being had to the accompanying drawing, forming a part thereof.

In the drawing:

Figure 1 illustrates a side view of the vacuum pressure bottle, or similar article, embodying my invention.

Figure 2 is a front view, and

Figure 3 is a top view thereof.

I claim:

The ornamental design for a vacuum pressure bottle, or similar article, as shown.

WALFRED F. WESTERLIND.
